UNITED STATES PATENT OFFICE.

ANTHONY E. MAGORIS, OF BINGHAMTON, NEW YORK.

CORSET-WAIST.

SPECIFICATION forming part of Letters Patent No. 687,536, dated November 26, 1901.

Application filed November 13, 1900. Serial No. 36,378. (No model.)

To all whom it may concern:

Be it known that I, ANTHONY E. MAGORIS, a citizen of the United States of America, residing at Binghamton, in the county of Broome and State of New York, have invented certain new and useful Improvements in Corset-Waists, of which the following is a specification.

My invention relates to an improvement in corset-waists, and it combines the functions of a shoulder-brace, a form-corrector, and supporter, and is adapted to be worn with or without corsets, and while made in various sizes is capable of a wide range of adjustments to the wearer's form.

Among the advantages of this invention may be mentioned the fact that the garment fits the body perfectly and adjusts deformed parts by applying gentle but constant pressure. It is capable of independent adjustment on opposite sides and in various parts to suit the requirements. Furthermore, it is a hygienic appliance adapted to correct unnatural postures of the body and by applying tension and pressure at the required point resulting in lifting of the chest-walls and allowing free action of the heart and lungs. By the adjustment of the armholes and the pressure at the arms and shoulders the tension on the strong muscles on the arms and chest in front is regulated and by the constant elastic pressure the shoulders are made to retain or regain their true position. It is a well-known fact that if the shoulder-blades lie flat on the back of the thorax or ribs the chest must be proportionately lifted up and expanded and breathing made easy and the heart action more natural. It is a primary object of my invention to insure this action.

With the foregoing objects in view my invention consists in certain novel features of construction and combinations of parts, which will be hereinafter described, and pointed out in the claims.

In the accompanying drawings, Figure 1 is a view in perspective of one form of my invention. Fig. 2 is a view in rear elevation. Fig. 3 is a view in front elevation of another form of the invention. Fig. 4 is a view of still another form of the invention, showing an abdominal supporter in connection there-

with. Fig. 5 is a detail of the manner of fastening the band, and Fig. 6 is a sectional detail view showing the padding in the straps. 55

A represents the back, made of suitable material cut to fit the form and extending from the base of the neck as far down the back as desired, it being of suitable width and preferably narrower than the usual width of a 60 jacket or dress back. This back is stiffened and supported by stays 1 1, sewed into the material of the back as closely together as the particular garment requires and according to the taste and requirement of the wearer 65 of the garment. The back is divided lengthwise through the center over the spine and is provided at each of the inner edges with eyelets 2 2 to admit of lacing together, as is shown, by the corset-string 3. 70

From each side edge of the back at a point a little below the arms a broad band 4 is extended forward to the middle line in front of the body, where the two parts are adapted to be fastened together by means of hooks 75 and eyes 5 and 6 or other equivalent fastening devices, thus forming a support around the body just under the breasts. Several of these eyelets are provided in order to allow for the adjustment to the wearer's size, and 80 the eyelets preferably extend only through the outer ply of the material of which the band in which they are located is composed, so that the ends of the fastening devices are covered and do not extend through in contact with the garments or the flesh of the wearer. These bands are so formed and braced by means of vertical stays 7 7, sewed or otherwise secured therein, that they form supports for the bust when desired. By means 85 of the lace at the rear and the series of eyelets or fastening devices in front the garment can be adjusted to a nicety and with ease and facility and at the same time afford a perfect support and comfort to the wearer. In 90 addition to the eyelets or fastening devices described at the end of one of these bands one or more rows of eyelets 9 9 are formed just in front of the arm and disposed horizontally, or approximately so, for a purpose 95 to be described hereinafter. 100

Just below the eyelets just mentioned two strips of material 10 10 are secured, one on each band. These strips extend about hori-

zontally from a point at or near the side edge of the back forward part way the length of the band, and in them a series of eyelets 11 11 are arranged for a purpose which will be 5 subsequently mentioned. These strips are stitched or otherwise securely fastened to the bands, and, as in the end of one of the bands, as described, the eyelets preferably extend through the strips only and not through the 10 bands.

From the upper ends of each back section a strap 12 extends forwardly over the shoulder, and from the point where this strap terminates at the top of the shoulder an elastic 15 strap 13 extends downwardly. This elastic strap may be single or double ply, and in any event has sufficient width, length, and strength to act as an elastic support over the front surface of the shoulder to attach to the 20 bands 4 4, and for this purpose the elastic straps are provided at their lower ends with a hook or other fastening device 14, adapted for engagement with the eyelets 9 9 at the upper edge of the bands 4 4, the hook being 25 inserted in the eyelet which most naturally falls opposite it, according to the size of the arm or the position the band takes about the body of the wearer. In this way the strap over the shoulder is rendered free of movement, constantly adjusting itself to the movements of the body very much like the shoulder-strap of an ordinary shoulder-brace or pair of suspenders. A cushion-sleeve 15 is 30 preferably made to cover this elastic part for the purpose of protection against too much rubbing or cutting or pressure on the part in front of the shoulder. The padded sleeve is made removable, so that it may be washed when desired.

40 From points on the back at or near the arm-holes tension-bands 16 16 are securely fastened. These bands extend straight across the shoulders and are adapted to be drawn up at the center and fastened by means of a 45 buckle or similar fastening device 17. From the same points 18 18, preferably where the straps or bands 16 16 are secured and, if desired, the same piece of material, diagonal bands 19 19 extend diagonally in opposite directions, crossing each other at the center, they being provided with hooks 20 20 or similar fastening devices at their ends, whereby to engage one of the eyelets 11 11 in the strips 10 10. In this way the bands at the back 50 may be adjusted to apply a gentle strain or pressure upon the shoulders and other parts of the form as may be desired to give erectness to the figure and cause the shoulders to be thrown back into their proper position.

60 When the garment is desired as a support to the spine at any distance down, the back A A may be lengthened, as shown in Fig. 3, to extend down as far as desired for the particular requirements of the case, and extra 65 straps 21 21 are fastened to the edges of these extensions and adapted to be secured together at the front by means of a hook or

buckle 22 or equivalent fastening device, as desired.

In lieu of the construction just described 70 provision may be made for the attachment of an abdominal supporter 24, as shown in Fig. 4, in which event instead of the straps 21 21 broader bands 25 are provided, forming an extension of the sides, and on these one or 75 more straps 26 are secured for buckling or fastening on and adjusting the abdominal supporter. The abdominal supporter can be made with or without an elastic gore 27 and of any desired width and shape, and can also 80 be provided with means for the attachment of the hose or other garments or appliances. It may also be mentioned that pendent straps, as shown in Fig. 1, may be removably attached to the lower end of the back of the 85 waist should occasion require their use at any time. When employed, a convenient form is that illustrated in Fig. 1, which consists of straps having hooks at their upper ends to enter eyelets 28 in the lower edges of the back 90 and eyelets 29 29 in their lower ends.

The garment thus constructed is light and of skeleton form and capable of being worn over or under corsets, or can be used in place of corsets. As set forth, the parts are capable 95 of independent adjustment at various points to accommodate the wearer or to adjust to the parts which they are intended to support. The garment is soft and flexible, thus yielding readily to the motion of the body. Also 100 it is effectual in accomplishing the functions ascribed to it.

It is evident that slight changes might be made in the form and arrangement of the several parts described without departing from 105 the spirit and scope of my invention, and hence I do not wish to limit myself to the exact construction herein set forth; but,

Having thus fully described my invention, what I claim as new, and desire to secure by 110 Letters Patent, is—

1. As an article of manufacture, a waist having broad bands which meet and are adjustably secured together in front of the body and shoulder-straps extending over the shoulders, adjustably connected with these broad bands, and cushioned sleeves removably secured on said shoulder-straps.

2. As an article of manufacture, a corset-waist provided with bands adapted to extend 115 forwardly around the wearer's body and adjustably secured in front, whereby the size may be increased or decreased, shoulder-straps extending from the upper ends of the back of the corset-waist, over the shoulders 120 and adjustably secured to the bands in front, means on the bands whereby the shoulder-straps may be laterally adjusted and transverse tension-bands secured at their opposite ends to each side of the back of the corset-waist and extending from the armholes transversely across the back of the waist, these 125 bands adjustably secured together at their meeting ends, centrally of the back of the

waist, whereby but one adjustment is necessary.

3. As an article of manufacture, a corset-waist comprising a back, shoulder-straps secured to the back, their lower ends secured to the waist and laterally adjustable thereon, and tension-straps extending transversely across the back of the garment toward each other and adjustably secured together at their meeting ends, in the center of the back of the garment whereby an equal tension is simultaneously exerted on both sides of the waist, by one adjustment.

4. As an article of manufacture, a garment provided with shoulder-straps, bands to which the shoulder-straps are secured and with relation to which the straps are laterally adjustable, and cushioned sleeves slidably mounted on each shoulder-strap.

5. As an article of manufacture, a waist comprising a back and shoulder-straps adapted to be secured at their lower ends to the waist, tension-straps extending transversely across the back of the garment and adjustably secured together at their ends and a cushion-sleeve removably attached to each shoulder-strap.

6. As an article of manufacture, a corset-waist comprising a back, bands extending forwardly from the sides of the back of the waist and adjustably secured together in front, shoulder-straps extending from the upper ends of the back forwardly over the shoulders and adjustably secured to the bands in front and bands secured to the back of the waist at the armholes, those bands extending diagonally downward across the back, crossing each other in the approximate center thereof, and thence extending forwardly under the armholes, their ends adjustably secured to the corset-waist bands in front.

7. As an article of manufacture, a corset-waist comprising a back, bands secured to the back of the waist and extending around the sides to the front of the wearer's body, where they are adjustably secured together, shoulder-straps secured to the upper rear portion of the waist, these straps passing over the shoulders and adjustably secured to the bands in front for the support of the corset-waist, and diagonal straps secured to the back of the waist and extending downwardly across the back of the waist, crossing each other in the approximate center thereof, and thence under the armholes, a series of protected fastening means on the bands securing the corset-waist in front, the ends of the diagonal bands being adjustably held in any one of the series of fastening means.

8. As an article of manufacture, a corset-60
waist comprising a back elongated at its lower end, upper bands extending forwardly and adjustably secured in front, shoulder-straps secured to and supporting the waist, the shoulder-straps having a lateral adjustment 65
with respect to the bands to which their free ends are secured, straps located on the sides of the elongated portion of the back on the elongated portion, and an abdominal supporter adjustably secured to the elongated 70
portion by means of the straps, whereby it is simultaneously fastened and adjusted, the abdominal supporter provided with an elastic gore formed in its front portion.

9. As an article of manufacture, a garment 75
consisting of a back divided centrally, bands integral with the back and extending forwardly, the bands adjustably secured to one another in front, shoulder-braces secured to the back and extending over the shoulders, 80
their ends adjustably secured to the bands in front, a transverse strap secured to the back below the shoulder-braces and adjusting means on the transverse strap.

10. As an article of manufacture, a garment 85
consisting of a back divided centrally, bands integral with the back and extending forwardly, the bands adjustably secured to one another in front, shoulder-braces secured to the back and extending over the shoulders, 90
their ends adjustably secured to the bands in front, a transverse strap secured to the back below the shoulder-braces, adjusting means on the transverse strap, and diagonal straps secured to the back, these straps crossing each 95
other and adapted to be adjustably secured to the bands at the sides thereof.

11. As an article of manufacture, a garment consisting of a back divided centrally, bands integral with the back and extending forwardly, the bands adjustably secured to one another in front, shoulder-braces secured to the back and extending over the shoulders, 100
their ends adjustably secured to the bands in front, a transverse strap secured to the back 105
below the shoulder-braces and adjusting means on the transverse strap, the band so constructed that the adjusting devices cannot extend entirely through the band, but are prevented from contact with parts beneath 110
the belt.

In testimony whereof I have signed my name to this specification in the presence of two subscribing witnesses.

ANTHONY E. MAGORIS.
